UNITED STATES PATENT OFFICE.

ARTHUR J. SMITH, OF HAZLETON, PENNSYLVANIA.

AUTO RADIATOR COVER.

Application filed April 9, 1925. Serial No. 21,918.

To all whom it may concern:

Be it known that I, ARTHUR J. SMITH, a citizen of the United States, residing at Hazleton, in the county of Luzerne and State 5 of Pennsylvania, have invented a new and useful Auto Radiator Cover, of which the following is a specification.

This invention relates to radiator protectors to be used in connection with the 10 radiators of motor vehicles.

The primary object of the invention is to provide a protector including a curtain which may be adjusted to various heights with respect to the radiator so that the volume of air drawn through the radiator by 15 the usual fan may be varied to meet various changes of weather conditions.

Another important object of the invention is to provide means for holding the curtain 20 taut at all times to insure against the same flapping against the radiator, while in use.

A still further object of the invention is the provision of adjustable brackets, whereby 25 the device may be used in connection with radiators of various sizes.

With the foregoing and other objects in view which will appear as the description proceeds, the invention resides in the combination and arrangement of parts and in the 30 details of construction hereinafter described and claimed, it being understood that changes in the precise embodiment of the invention herein disclosed, may be made within the scope of what is claimed, without 35 departing from the spirit of the invention.

Referring to the drawing:

Figure 1 is an elevational view illustrating 40 a radiator curtain constructed in accordance with the invention.

Figure 2 is a side elevational view of a radiator equipped with a curtain constructed in accordance with the invention, the radiator being partly broken away.

Figure 3 is a sectional view taken on line 45 3-3 of Figure 1.

Figure 4 is a perspective view of the movable section of the fastening member.

Referring to the drawing in detail, the 50 reference character 5 indicates a radiator of a motor vehicle, the same being of the usual construction and embodying the usual radiator shell 6.

The device includes a pair of arms indicated at 7 which have integral hook members 8 formed at their inner ends, which

hook members are adapted to be positioned around the inner edge of the radiator shell 6, in a manner as clearly shown by Figure 2 of the drawing.

Formed in each arm 7 is an elongated opening 9, the openings 9 being designed to accommodate the rod 10, which connects the arms 7, nuts 11 being provided on the ends of the rod 10 to hold the arms 7 in proper spaced relation with each other and eliminate any possibility of rattling of the arms 7, due to vibrations of the engine.

Positioned on the rod 10 are depending arms 12 which arms are provided with spaced openings 13 that accommodate the shaft 14 of the roll 15 on which the curtain 16, is wound. It is to be understood that the roll 15, is of the spring roll type so that as the curtain 16 is unwound from the roll 15, the curtain will be placed under tension to the end that when the curtain is released, it will automatically wind on its roll.

Set screws 17 extend through the upper ends of the arms 12 and engage the rod 10 to the end that the arms 12 may be adjusted longitudinally of the rod 10 so that rolls of various lengths may be positioned between the arms, the set screws acting to hold the arms in their positions of adjustment.

The keeper forming a part of the invention embodies an elongated bar 18 which is adapted to be supported by the radiator, bolts 19 being provided and extended through the bar at various positions throughout the length of the bar 18, the bolts passing through the spaces between the coils of the radiator as clearly shown by Figure 2 of the drawing. Thus it will be seen that due to this construction, the bar 18 may be readily and easily secured or removed from the radiator.

Stamped from the bar 18 are hook members 20 which are arranged throughout the length of the bar 18 and disposed in spaced relation with each other to be engaged by the securing member 21 carried by the curtain. The securing member 21 is disposed intermediate the ends of the rod 22 which is positioned in a suitable pocket formed at the upper end of the curtain 16 to brace the cover throughout its width and prevent wrinkling thereof while in use.

From the foregoing it will be obvious that should it be desired to expose the upper portion of the radiator the member 21

may be positioned over a hook member 20 in such a way as to hold the upper end of the curtain at a point as shown by Figure 1 of the drawing. In warm weather should it be desired to admit air to the entire radiator surface, the curtain may be moved so that the member 21 will lie over the hook member at the base of the bar 18.

To facilitate the use of the curtain 16, a finger piece 23 is provided so that the operator may readily operate the curtain to position it over the hook members 20 or remove it therefrom.

I claim:

1. A radiator protector comprising a pair of spaced arms, arms adjustably connected with the first mentioned spaced arms, means for securing the first mentioned arm to the radiator of a motor vehicle, the second mentioned arms adapted to be adjust-

ed towards and away from the radiator, a curtain carried by the last mentioned arms and adapted to move adjacent to the radiator, and means for holding the curtain in various positions of adjustment. 25

2. A radiator protector comprising a pair of spaced arms, having elongated openings, means for removably securing the arms to the radiator, a rod supported within the openings to connect the arms, arms adjustably supported on the rod, a roll supported between the last mentioned arms, a curtain on the roll, and means for securing the free end of the curtain adjacent to the radiator. 30

In testimony that I claim the foregoing as my own, I have hereto affixed my signature. 35

ARTHUR J. SMITH.
